UNITED STATES PATENT OFFICE

PATRICK J. FITZGERALD, OF TORRINGTON, CONNECTICUT, ASSIGNOR TO THE FITZGERALD MFG. COMPANY, OF TORRINGTON, CONNECTICUT, A CORPORATION OF CONNECTICUT

DESIGN FOR A CASING FOR A ROTARY CUTTING IMPLEMENT

Application filed December 6, 1932. Serial No. 46,313. Term of patent 14 years.

To all whom it may concern:

Be it known that I, PATRICK J. FITZGERALD, a citizen of the United States, residing at Torrington, in the county of Litchfield and State of Connecticut, have invented a new, original, and ornamental Design for a Casing for a Rotary Cutting Implement, of which the following is a specification, reference being had to the accompanying drawing, forming a part thereof.

Figure 1 is a perspective view of the article showing my new design, and

Figure 2 is a rear view showing thereof.

I claim:

The ornamental design for a casing for a rotary cutting implement, as shown.

PATRICK J. FITZGERALD.
